UNITED STATES PATENT OFFICE.

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS.

SWITCH BUTTON.

Application filed December 27, 1926. Serial No. 157,184.

This invention relates to improvements in switch buttons and more particularly to buttons of this character which are used in connection with rotary electrical switches.

5 An object of applicant's invention is the production of a switch button which may be quickly assembled and attached to the stem of a rotary snap switch, thereby effecting a great saving in time.

10 Another object of applicant's invention is the production of a button for a rotary snap switch which will resiliently secure the cover for the movable parts in place.

Another object of applicant's invention 15 is the production of a construction which will permit the use for switch buttons of materials such as porcelain and others in which metals are not readily molded or cast.

20 A further object of my invention is the provision of a switch button of the above type including in its construction a non-conductive body having a bore, a sleeve positioned within the bore with a coil spring 25 surrounding the same, together with improved means seated within the outer open end of the bore cooperating with the sleeve whereby to prevent displacement of the sleeve.

30 A still further object of my invention is the provision of a switch button wherein the relative parts of the same are so constructed and arranged that they may be quickly and readily assembled and when in 35 assembled position retained against displacement.

Many other objects and advantages of the 40 construction herein shown and described will be obvious to those skilled in the art from the disclosure herein given.

To this end my invention consists in the novel construction, arrangement and combination of parts herein shown and described and more particularly pointed out in 45 the claims.

In the drawings, wherein like reference characters indicate like or corresponding parts:

50 Fig. 1 is a front elevation of a rotary type switch illustrating my improved button applied thereto;

Fig. 2 is a longitudinal section through the button;

Fig. 3 is an end elevation;

Fig. 4 is a perspective view of the washer plate; 55

Fig. 5 is a longitudinal section illustrating in modified form a part of the invention;

Fig. 6 is a view similar to Fig. 5 illustrating another form of the invention; 60

Fig. 7 is a view similar to Fig. 5 illustrating still another form of the invention; 65

Fig. 8 is a view similar to Fig. 5 illustrating still another form of the invention.

Referring to the drawings, I have illustrated in Fig. 1 my improved switch button applied to a rotary type of electric switch generally indicated by the reference character 1, and my improved switch includes a central body portion 2 having reduced wings 3 at opposite sides thereof forming finger pieces whereby the button may be readily grasped for imparting rotary movement thereto. The body of the button is formed with a bore 4 and one face of the body is provided with a substantially circumferential rib 5 surrounding the outer opening of the bore 4 so as to provide a substantially 70 larger entrance to the bore. 75

Positioned within the bore 4 is an internally threaded sleeve 6, the inner end of which is solid in cross section and provided with a substantially rectangular head 7 which fits snugly within the bore, and as the head is somewhat larger than the exterior of the sleeve 6 the sleeve may be spaced from the walls of the bore as shown in Fig. 2. 80

As stated heretofore, the sleeve 6 is internally threaded and removably arranged in the threaded sleeve is the bearing member 8 which supports the movable contact member of the rotary switch. Surrounding the sleeve and disposed within the bore 4 85

is a coil spring 9, the inner end of which bears against the head 7, and said spring is retained within the bore by means of the plate 10 which is positioned within the chamber formed by the rib 5 whereby to 90 close the outer end of the bore, and as the plate 10 is formed with a central opening 11 which snugly receives the sleeve 6, it will be apparent that the spring 9 will be retained in its effective position within the bore. 95 The perimeter of the plate 10 is formed with a plurality of spring fingers 12 which incline away from the peripheral edge of the 100 105

plate toward their outer ends so that when the plate is positioned within the chamber formed by the rib 5 the outer ends of the fingers 12 will have a tendency to frictionally engage with the inner wall of the rib 5 and retain the plate 10 in its active position. It will be apparent from the above that when the sleeve 6 has been positioned within the bore, its head 7 snugly received within the bore, the coil spring 9 placed in position and the lock plate 10 fitted within the rib 5, the parts will be properly assembled and due to the interfitting engagement will be securely retained in position. The movable contact bearing member 8 may be quickly attached to the sleeve 6 or detached therefrom as desired, this part of the device being the well known type in use at the present time.

In Fig. 5 I have illustrated a slightly modified form of the invention wherein the relative construction of the parts are the same as in the preferred form, but in the form shown in Fig. 5 it will be noted that the inner wall of the rib 5' is formed with an annular bead 13 behind which the fingers 12 will position themselves after the plate 10 has been properly placed in the position over the outer end of the bore 4' so as to positively retain all parts of the device in their positions, this bead 13 being placed upon the inner wall of the rib 5' in case it should be found necessary not to rely wholly upon frictional contact upon retaining the parts in position. In Fig. 6, I have illustrated another form of the invention wherein the inner wall of the rib 5^a is formed with an annular notch 14, the off-set portion of the notch forming an annular shoulder against which the outer ends of the fingers 12 abut when the plate 10 is properly positioned so as to securely retain the plate in place. This notch 14 may be either formed as a single circumferential notch or as a series of spaced notches corresponding to the number of fingers on the plate.

In Fig. 7 I have illustrated still another form of the invention wherein the plate 10 is eliminated and the inner wall of the rib 5'' is formed with an annular recess 15 and instead of using the plate 10, I provide a substantially thick washer member 16, the peripheral edge of which is provided with a channel or recess 17 adapted to be positively disposed relative to the annular recess 15, and when the washer member 16 is placed within the rib 5'' a split ring 18 previously placed within the channel 17 will, when the washer 16 reaches the outer end of the bore in the body of the button, spring into the recess 15, or in other words, the outer edge of the ring will fit within the recess 15 so that the ring is positioned in such manner as to form a stop for the washer 16 and prevent its removal from the interior of the

rib 5'', thus retaining the parts of the button in proper assembled relation.

In Fig. 8 I have illustrated still another form of the invention wherein the inner wall of the rib 5^c is formed with an undercut groove 19 forming inclined side walls 20, and the plate 10' is of sufficient size to pass through the restricted mouth of the rib and the fingers 12 disposed on an incline relative to the upper face of the washer with their outer ends in biting contact with the inclined wall to retain the plate 10' against outward movement. The plate 10', however, may be made of resilient material and of a size larger than the mouth of the rib 5^c and sprung into the rib and disposed beneath the undercut wall if so desired.

From the foregoing description it will be apparent that I have provided a switch button which is comparatively simple in its construction. The button is of such construction that the body member which includes the wings 3, may be formed of any suitable non-conductive material such as hard rubber, bakelite, porcelain, or any vitreous material.

Having thus described my invention, it is obvious that various immaterial modifications may be made in the same without departing from the spirit of my invention; hence I do not wish to be understood as limiting myself to the exact form, construction, arrangement and combination of parts herein shown and described and uses mentioned.

What I claim as new and desire to secure by Letters Patent is:

1. A device of the character described including a body having a bore, a sleeve removably arranged in the bore, and a stop plate mounted on the sleeve and closing said bore, said stop plate having resilient fingers gripping the walls of said bore.

2. A button of the class described including a body having a bore therein, a sleeve removably arranged in the bore, a coil spring surrounding the sleeve, and stop plate mounted upon the sleeve for retaining the spring within the bore and the sleeve against lateral movement, said stop plate having resilient fingers gripping the walls of said bore.

3. In a button of the character described, a body having a bore therein, oppositely disposed wing portions on the body, the outer end of said bore being enlarged, a sleeve in the bore having a head at its inner end, a coil spring within said bore, a stop plate positioned within the enlarged end of the bore, and a plurality of projections on said stop plate having yielding contact with the wall of the bore.

4. A button of the character described, a body having a bore, a sleeve removably arranged in said bore, a stop plate arranged

within the outer end of the bore and embracing the sleeve, and resilient means on said plate for retaining said plate in active position.

5. A device of the character described including a body formed with a bore having an enlarged end, a sleeve movably arranged in the bore, a stop plate mounted on said sleeve and arranged in the enlarged end of

said bore, means on said sleeve and engaging said stop plate for urging said sleeve into said bore, and yieldable fingers on said plate for engagement with the wall of said bore to retain said plate in the bore.

In testimony whereof, I have hereunto signed my name.

THOMAS L. PARKER.
